James D. Burke and Fuller A. Crooks, Los Angeles, Calif.; said Burke assignor to A. Morgan Maree, Jr., Speed L. Post, Stanley E. Lindahl, and himself, all of Los Angeles County, Calif., as tenants in common

Application January 18, 1944, Serial No. 112,340

Term of patent 14 years

(Cl. D52—1)

To all whom it may concern:

Be it known that we, James D. Burke and Fuller A. Crooks, citizens of the United States of America, residing at Los Angeles, in the county of Los Angeles, State of California, have invented a new, original, and ornamental Design for a Torque Meter, of which the following is a specification, reference being had to the accompanying drawing forming a part thereof.

Fig. 1 is a front perspective view of a torque meter showing our new design,

Fig. 2 is a top plan view of the meter,
Fig. 3 is a left end elevational view thereof,
and

Fig. 4 is a right end elevational view of the same.

We claim:

The ornamental design for a torque meter, as shown.

JAMES D. BURKE.
